UNITED STATES PATENT OFFICE.

STANKO GJANKOVICH, OF NEW YORK, N. Y.

SPINNING DEVICE.

Application filed March 4, 1927. Serial No. 172,745.

This invention relates to a musical spinning device, and particularly to that class in which rotatable tops emit sounds produced by the passage of air through apertures therein. Its object is to provide an article of this character having means to maintain the base elements in vertical position, and other means to rotate, or spin them rapidly and to reverse the direction of rotation at intervals.

A further object is a means whereby tension is applied simultaneously to an assembled group of the rotatable units.

Other objects are, a novel winding element and a casing therefor.

The foregoing and other features of the device will be fully described in the following specification and illustrated in the accompanying drawings, in which:

Fig. 1 shows a side view of a rotatable unit.

Fig. 2 shows a top plan view of same.

Fig. 3 shows an enlarged vertical section on the line 3—3 of Figure 2. It illustrates the winding element, casing, and the spool therein contained.

Fig. 4 shows another form of the winding element in which a retracting spring is employed.

Fig. 5 shows a section on the line 5—5 of Figure 4.

Fig. 6 shows on a reduced scale, a side view of an assembly frame with the units mounted therein, and also illustrates the tension mechanism.

Fig. 7 shows a cross section on the line 7—7 of Figure 6.

Fig. 8 shows a top view of the elements illustrated in Figure 6.

Fig. 9 shows an enlarged perspective view of an upper holding clip with a fragment of a winding element casing and a supporting rod.

Fig. 10 shows an enlarged fragmentary view of a slotted tension spring.

Referring first to Figure 6 of the drawings, the invention comprises a frame 10, open at the sides and having horizontal rods as seen at 11 and 12 secured therein, and rotatable units as 13, 14, 15 etc. removably mounted on the aforesaid rods by means of upper clips as that seen at 16 in Figure 7, and by lower clips as that shown at 17 in the same figure. Winding element casings as those shown at 18, 19 etc. in Figure 6 are located on spindles as seen at 20, 21 etc. These casings are pro-

vided with upper and lower bearing bushings as seen at 22 and 23 in Figure 7. A pressure element 24 is slidably mounted in the said frame. This element has lateral arms as seen at 25, 26 etc., and slotted springs as that shown at 27, and again, enlarged in Figure 10. These springs press upon the upper bearing bushings, the degree of pressure being regulated by means of hand wheels as that shown at 28. This pressure element is supported at its ends by the screw shafts 29 and 30 as seen in Figure 6, these being threaded through the bosses 31 and 32 and guided by end brackets as that shown at 33 in Figure 7. The screw shafts are pivotally mounted at the bottom, having retaining base flanges as that shown at 34. It will be seen that the turning of the hand wheels raises, or lowers the pressure element as desired.

Referring again to the upper holding clips; these are secured to the base caps of the winding casings as seen in Figure 9. The lower clips have two tongues each as may be seen at 35 and 36 in Figure 6, and may be removed by simply lifting off from the supporting rods.

The detailed construction of the rotating units will now be described; referring first to Figure 1 of the drawings. The unit here shown has a base element 40 with tip 41 and with perforations in its side walls as shown at 42, 43 etc. Musical sound is produced by the passage of air through these perforations while the unit is in rapid revolution. A spindle 21 is secured to the top of the base element and passes upward through the winding casing 19, bearing bushings being provided as shown at 22 and 23. A finger grip 44 is affixed at the top of the spindle. A pull cord 45 with hand grip 46 is secured within the casing as seen in Figure 3, it being secured to a spool 47 which has flanges 48 and 49, and a central tube 50 which is tightly secured to the spindle 21 by the screw 51. The central tube abuts the bearing bushings 22 and 23 as shown and maintains the casing in its correct position on the spindle. A bottom cap 52 is screwed on to the casing 19, and to this cap is affixed the upper holding clip 16.

Units of the type described may be assembled in the frame as seen in Figures 6, 7 and 8, they being supported by means of the upper and lower clips as shown, and further secured in adjustable tension by the element 24. When so assembled, they may be caused

to rotate simultaneously by means of the grouped cords as seen at 53 and 54 in Figure 8. These cords being pulled by grasping the grip piece as that seen at 46, and 5 first pulling and then releasing, thus causing the spindles to revolve first in one direction and then in the opposite thereto, the cord which has the first been unwound, being rewound by the impetus given to the units. 10 The movement thus described produces a harmony of varying musical notes as the air passes through the several units.

Another form of winding element is shown in Figures 4 and 5, in which a re- 15 tracting spring 60 is secured at its top to the spool flange as seen at 61, and at its bottom to the base cap as seen at 62. When this spring is employed, it reverses the winding spool at the end of the pull and re-winds the cord in the same position as before.

The individual units may be removed 20 from the frame and operated alone if desired, by holding the casing element 19 in one hand while exerting the pull with the other.

While I have shown the preferred embodiment of the invention herewith, I do not wish to be held rigidly to the exact 25 details of construction as illustrated, but claim the right to such minor modifications as may come within the scope of the appended claims.

Having thus described my invention, 30 what I claim as new and desire to secure by Letters Patent is as follows:

1. In a device of the character described, 35 a suitable frame structure having horizontal supporting members mounted therein, and 40 removably affixed to the said supporting members, rotatable sound producing units, each of the said units comprising a base element, a vertical spindle, a winding element and a casing enclosing the same, and a cord 45 secured to the said winding element, the cords of the several units grouped together at their outer ends and having a common means for gripping in the hand, a pressure 50 element adjustably mounted in the said frame structure and having spring end members which are adapted to bear upon the said rotatable units and to limit their vertical play.

2. In a device of the character described, 55 a frame structure having horizontal supporting rods mounted therein, rotatable sound producing units removably affixed to the said supporting rods, winding elements 60 on the said rotatable units and casings enclosing the said elements, and a pressure element slideable vertically within the said frame structure and adjustable by means of threaded supporting shafts having hand grip members thereon; and the said pressure 65 element provided with lateral arm members

each terminating in a slotted leaf spring, which leaf springs engage the casings of the several rotatable units and exert a pressure thereon, cords secured to the winding elements of the said rotatable units, and means to pull the said cords simultaneously. 70

3. In a device of the character described, a rotatable sound producing unit comprising a hollow base element having perforations in the walls thereof, a vertical spindle a 75 flanged spool secured to the said spindle, a casing enclosing the said spool, an adjustable lower cap on the said casing and a clip member attached to the said cap, a cord secured to the flanged spool, and means to grip the free end of the said cord, and means to support the whole in an upright position. 80

4. In a device of the character described, a rotatable sound producing unit comprising a hollow base element having perforations in the walls thereof, a vertical spindle, a flanged spool secured to the said spindle, a 85 casing enclosing the said spool, an adjustable lower cap on the said casing and a clip member attached to the said cap, a coil spring attached to the said spool at one end and secured at the other to the aforesaid cap, a cord secured to the said flanged spool and means to grip the free end of the 90 said cord, and means to support the whole in an upright position, substantially as shown and described. 95

5. In a device of the character described, a rotatable sound producing unit comprising a hollow base element having perforations in the walls thereof, a vertical spindle secured to the hollow base element, a flanged spool secured to the said spindle, a casing 100 enclosing the said spool, an adjustable lower cap on the said casing, a clip member attached to the said cap, a cord secured to the flanged spool, a hand grip secured to the free end of the said cord, and means to support the whole in an upright position. 105

6. In a device of the character described, a rotatable sound producing unit comprising a hollow base element having perforations in the walls thereof, a vertical spindle secured to the hollow base element, a flanged 110 spool secured to the said spindle, a casing enclosing the said spool, an adjustable lower cap on the said casing and a clip member attached to the said cap, a coil spring attached to the said spool at one end and secured at the other to the aforesaid cap, a cord secured to the said flanged spool and means to grip the free end of the said cord, and a frame for supporting the whole in an up- 115 right position, substantially as shown and described. 120

In testimony whereof I have affixed my signature.

STANKO GJANKOVICH.
